UNITED STATES PATENT OFFICE.

OTTO B. WEDELL, OF ELGIN, ILLINOIS.

EYEGLASS-CHAIN REEL.

938,359.

Specification of Letters Patent. Patented Oct. 26, 1909.

Application filed November 16, 1908. Serial No. 462,938.

To all whom it may concern:

Be it known that I, OTTO B. WEDELL, a citizen of the United States, residing at Elgin, in the county of Kane and State of Illinois, have invented certain new and useful Improvements in Eyeglass-Chain Reels; and I do hereby declare the following to be a full, clear, and exact description of the invention, such as will enable others skilled 5 in the art to which it appertains to make and use the same.

My invention relates to improvements in eye glass chain-reels and is a specific improvement over the construction described 15 and claimed in my application filed July 6, 1908, Serial No. 442,209.

The object of my invention is to provide a simple and compact chain reel to which eye glasses may be attached by means of a 20 suitable fastening to the outer end of the chain and easily reeled and unreeled and latched and unlatched.

When in use, it is pinned to the garment of the wearer by an ordinary catch pin, 25 lying parallel to and attached to the back of the device, with the guide slot and latch notch down.

With this object in view, my invention consists in the construction and combinations 30 of parts as hereinafter described and claimed.

In the accompanying drawings—Figure 1 is a longitudinal section of my improved reel. Fig. 2 is a bottom plan view thereof, 35 parts being broken away. Fig. 3 is a cross section thereof on the line 3—3 of Fig. 1, looking in the direction of the arrows, and Fig. 4 represents a combined stop and chain tip.

40 *a* represents a case which is provided with a longitudinal guide slot *b* and a latch notch *u*. The case *a* is provided with heads *d* and *e* and finishing heads *v* and *w*.

45 *f* represents a pin secured to the back of the case *a* for the purpose of securing the device to the clothing of the user. This pin is of the type of the ordinary safety pin.

Rigidly mounted in the heads *d* and *e* is a 50 shaft *f* having reduced and shouldered ends. Around the shaft *f* is coiled a spring *g*, one end *h* thereof being fastened to the shaft *f* and the other to the winding drum at *n*. Surrounding the shaft *f* is a drum *i* provided on its outside with a spiral groove *j*. 55 This drum is hollow and is mounted on heads *k* and *m*, the former being recessed

on its inside face and projecting over a shoulder on the shaft *f* so as to prevent the spring *g* from getting in between said shoulder and the inner face of the head *k*. The 60 whole drum construction is revolvably mounted on the shaft *f*, space being afforded within the drum for the reception of the spring *g*, so that the drum may revolve freely under the influence of said spring, 65 unless it is latched by means hereinafter described.

o represents the chain to which the eyeglasses (not shown) are attached by the means shown in Fig. 4, in which *l* represents a combined stop and chain tip with a hole drilled in it to receive the end of the chain *o*, said chain being fastened by a pin *s*, passing through the tip and chain at right angles thereto. *x* in dotted lines represents 75 a hole to receive any style of snap that may be desired. In the drawing a figure 8 snap is shown. The other end of the chain *o* is fastened to a pin *p* carried by the drum.

The means for latching and unlatching 80 the drum will next be described.

q represents a combined chain guide and sliding collar, which is provided with a hole *t*, through which and through the guide slot *b* the chain *o* passes, the hole *t* acting as a 85 guide for the chain. The collar *q* is adapted to slide freely over the drum *i* between said drum and the outer case *a*, and is provided with a guide pin, *y*, projecting inwardly from said collar and fitting into the spiral 90 groove *j* on the drum. The part *y* may be inserted into the collar *q* or may be a projection punched up from the collar. *r* represents another guiding pin, which, however, 95 may be omitted. As the drum *i* revolves, it causes the collar *q* to slide on account of the guide pin. Said sliding collar *q* is also provided with a latch pin *z* projecting outwardly and adapted, under certain conditions, to engage the latch notch *u* in the 100 case *a*.

The operation is as follows: In the position shown in Fig. 1, the parts are shown when the chain is pulled out to its full length and the drum *i* latched, as happens 105 when the eye glasses are in use. If the user wishes to have the eye glasses reeled up until they reach the case *a*, he gives a short downward pull upon the chain, holding it taut, and then gives a slight upward lift. This 110 disengages the latch pin *z* from the latch notch *u* in the case *a*, allowing the reel to

wind up a portion of the chain until the latch pin *z* has passed the latch notch *u*. The user then releases the chain and the spring *g* rotates the drum *i*, coiling up the chain in the groove *j*. As the chain is reeled up the sliding collar *q* travels along the drum *i* and the latch pin *z* slides along in the guide slot *b* in the case *a*.

This application is distinguished from my former application above referred to in the following particulars: 1. A case having a guide slot and latch notch, said case being provided with a finishing head on each end and a single pin for securing it to the clothing of the user. 2. A recessed head for the winding drum, fitting over a shoulder on the supporting stationary shaft. 3. A combined chain guide and sliding collar, said collar being provided with guiding means, a hole for the chain to pass through and latching means. 4. A combined stop and chain tip provided with means for securing it to the free end of the chain, and means for securing a snap to it.

25 I claim:

1. In an eye glass chain reel, the combination of a case provided with a guide slot and latch notch, a spirally grooved drum revolvably mounted therein, a spring tending to rotate said drum in one direction, a chain attached to said drum and a combined chain guide and sliding collar provided with means co-operating with the slot and adapted to seat in the notch in the case for preventing the rotation of said drum, substantially as described.

2. The combination of a case provided with a guide slot and latch notch, said case

being provided with means for securing it to the clothing of the user, a spirally grooved drum revolvably mounted therein, a spring normally tending to rotate said drum in one direction, a chain, one end of which is attached to said drum, a combined chain guide and sliding collar provided with a perforation through which said chain passes, and latching means, carried by the sliding member and adapted to travel in said slot and at times to engage in said notch, substantially as described.

3. The combination of a case, provided with a guide slot and latch notch, said case being provided with a finishing head on each end and with means for securing it to the clothing of the user, a shaft rigidly mounted in said case, a spirally grooved drum revolvably mounted on said shaft, and provided with heads, one of which is recessed, a spring having one end attached to said shaft and the other end to said drum, a chain, a combined chain stop and chain tip, said chain being secured at one end to said drum and at the other end to said stop and chain tip, a combined chain guide and sliding collar, said sliding collar being provided with a hole through which said chain passes, and with guiding means and latching means, said latching means being adapted to travel in said guide slot and to engage said latch notch at times, substantially as described.

In testimony whereof, I affix my signature, in presence of two witnesses.

OTTO B. WEDELL.
